UNITED STATES PATENT OFFICE

2,406,643

CONVECTION HEATER

Benjamin Spieth, Racine, Wis., assignor to Modine Manufacturing Company, Racine, Wis., a corporation of Wisconsin

Application September 2, 1943, Serial No. 500,877

2 Claims. (Cl. 257—136)

1

This invention relates to a convection heater.

One object of the invention is to provide a cabinet having an air inlet opening at its bottom and a hot air outlet opening at its top, together with a heat transfer element disposed adjacent the open bottom of the cabinet and adapted to heat air passing upward through the cabinet.

Another object is to provide a damper controlled auxiliary air inlet to the cabinet of the heater and disposed above the heat transfer element whereby the heat output of the cabinet may be varied from a maximum to a value approaching zero.

Another object is to provide an auxiliary air inlet to the cabinet protected by a grille, together with a damper to regulate the volume of air entering the auxiliary air inlet, the damper being so mounted that it may close the grille when in one extreme position and permit an unrestricted flow of air through the heating element and cabinet, or it may cover the heating section wholly or in part in other positions and permit an unobstructed flow of air through the auxiliary air inlet, together with means for adjusting the damper to any desired position between its two extreme positions.

Another object is to provide a convection heater that can be constructed economically and with a minimum number of parts and one that is highly efficient in operation.

With these and other objects and advantages in view, this invention consists in the several novel features hereinafter fully described and claimed.

One embodiment of the invention is illustrated in the drawings accompanying this specification in which:

Fig. 1 is a front elevation of the heater;

Fig. 2 is a vertical cross section taken on the line 2—2 of Fig. 1;

Fig. 3 is a vertical longitudinal section taken on the line 3—3 of Fig. 2, and showing part of the heater broken away. Figs. 2 and 3 are upon a slightly enlarged scale;

Fig. 4 is an enlarged detail horizontal section taken on the line 4—4 of Fig. 2, illustrating the damper controlling mechanism and a fragment of the damper itself;

Fig. 5 is a vertical cross section of the damper controlling mechanism and damper showing the latter in its closed position with respect to the auxiliary air inlet;

Fig. 6 is a detail horizontal section taken on the line 6—6 of Fig. 2;

Fig. 7 is an enlarged fragmental vertical cross

2

section through the front wall and damper illustrating the hinge connection between them; and

Fig. 8 is an enlarged fragmental vertical cross section through a certain indicator blade and plate used in connection with the damper.

Referring to said drawings, which are merely illustrative of one embodiment of the invention, the reference character 10 designates the cabinet of the heater, which is desirably rectangular in form and composed of sheet metal. Conveniently the cabinet may comprise a front wall 11 having rearwardly extending flanges 12 at its side edges, and a rear wall 13 formed with forwardly extending side wall flanges 14 that overlap the front wall flanges and are secured thereto in any desirable manner.

One form of securing means between the overlapping side wall flanges 12—14 is illustrated in Figs. 2 and 6 and comprises L-shaped brackets 9, one spot welded or otherwise rigidly secured to each side wall flange 14 and formed with a flanged arm 8 which bears against the inner face of the front wall. Bolts and nuts 7 may be employed for fastening the front wall to the brackets 9. Shoulder rivets 15a secured to the flanges 14 and extending through notches in the flanges 12, may be employed for fastening together the lower ends of the front and back sections of the cabinet.

30 The metal sheet that forms the front wall 11 may be of greater length than that required to form the front wall, and its upper end may be bent rearward to extend in an inclined direction and form the top wall 11a of the cabinet. The 35 top wall is provided with an air outlet opening 15 which is protected by a grille 16. Conveniently the grille 16 may comprise angle iron members 16a spot welded or otherwise rigidly secured to the top wall adjacent the front and rear edges 40 of the opening therein, and spaced bars 16b intermediate the angle iron members and rods or wires 16c that extend through the angle iron members and bars. The metal which forms the top wall 11a is bent downwardly at the side edges 45 of the top wall to form flanges 12a that are in effect continuations of the flanges 12 of the front wall and overlap the side wall flanges 14 as is seen at 12b in Fig. 3. At the places where the flanges 12 and 12a—14 overlap each other the side wall flanges 14 are offset inwardly to receive the overlapping portions of the flanges 12 and 12a, whereby the outer faces of the side walls may be flush. The rear end of the top wall may be bent downwardly to provide an upright flange 11b that extends contiguously with the in-

inner face of the rear wall 13, and an air seal 11c may be provided at the upper inner corner of the cabinet.

For reinforcing the front wall a horizontally extending V-shaped reinforcing member 10a may be spot welded or otherwise secured to the inner face of the front wall. The rear wall may be reinforced with horizontally extending channel bars 13a, riveted or otherwise fastened to the rear wall. Conveniently the heater is supported above the floor of the room in which it is contained by mounting it on a wall of the room by bolts which pass through the channel bars 13a. A sheet of heat insulating material 13b may be secured to the outer face of the rear wall to prevent an excess amount of heat from radiating from the rear wall.

Adjacent the open bottom of the cabinet is a heat transfer element 17 which is supported from the side walls of the cabinet, and in the present embodiment of the invention the heat transfer element comprises a plurality of parallel fluid conducting tubes 18, 18a headers 19-20 connected to the ends of the tubes and heat radiating fins 21-22 through which the tubes extend. The headers are of particular construction and are more particularly shown and described in my co-pending application Serial No. 500,876, filed September 2, 1943, to which reference may be had for a fuller description.

Briefly, each header comprises a seamless tube of suitable dimensions of octagonal, hexagonal or other many-sided configuration. The bore 23 of the header is cylindrical and the wall thereof is threaded at both ends for the reception of a pipe fitting 24 or 24a or a screw plug 25 or 25a. Holes are drilled in the sides of each header for connection with the ends of the tubes. The several parts of the heat transfer element may be brazed together or otherwise integrally united in accordance with the common practice.

As illustrated, the heat transfer element is intended for use in a two pipe heating system. The elbow fitting 24 connects with a steam or hot water supply pipe 28 and the elbow fitting 24a connects with a return pipe 30. If desired an air valve 31 may be provided at the discharge end of the heat transfer element and in that event the screw plug 25a at the discharge end may be drilled and tapped for the reception of the threaded nipple of the air valve.

For giving additional support to the headers, the end fins 21 are preferably constructed of heavier gauge metal than the intermediate fins 22, and the lower ends of these end fins extend at right angles to the main upright parts 33 thereof to provide horizontal flanges 34 which are formed with holes for the reception of the lower ends of the headers.

Secured to the side walls 14 of the cabinet and extending from the front wall to the back wall, are bracket members 35 which are formed with oppositely directed upright portions 36 and 37 bent at right angles to their horizontal portions 38. The upright portions 36 are contiguous with the side walls of the cabinet and are rigidly secured thereto as by spot welding or otherwise and the upright portions at 37 are spaced inwardly from the side walls a distance somewhat greater than the diameter of the headers, and the lower ends of said upright portions 37 of the bracket members are bolted or otherwise rigidly secured to the upper ends of the end fins 21 of the heat transfer element as by bolts and nuts 39. The inward spacing of the upright portions 37 of the

bracket members provides space for the reception of the headers close to the side walls of the cabinet and also provides a confined passageway for the ascending heated air that rises from the heat transfer element.

In the front wall 11 of the cabinet, directly above the heat transfer element, is an auxiliary air inlet 40 which is protected by a grille 41 that extends across the opening, directly behind it. Desirably the grille may comprise horizontal angle iron bars 42, intermediate bars 43 and vertical rods or tubes 44 extending through said bars. The horizontal flanges of the angle bars 42 are coincident with the upper and lower edges of the auxiliary air inlet. Upright bars 45 that are coincident with the side edges of the auxiliary air inlet connect the angle iron bars 42 and together with said angle iron bars provide a throat which extends inwardly from the marginal edges of the auxiliary air inlet. The grille is fastened to the inner face of the front wall by spot welding the angle iron bars 42 thereto or by any other suitable fastening means.

For regulating the volume of air admitted to the cabinet through the auxiliary air inlet, a damper 46 is provided for closing or partially closing the auxiliary air inlet or for leaving said inlet entirely free and clear for the unrestricted flow of air therethrough.

Desirably the damper is in the form of a rectangular piece of sheet metal having one section 47 thereof bent at a slight angle to the main section 48. The damper is hingedly connected on a horizontal axis to an angle shaped hinge plate 49 which is spot welded or otherwise secured to the front wall of the cabinet. Cooperating with said hinge plate 49 is a hinge plate 50 secured to the inner or under side of the damper. The adjacent ends of both of these hinge plates are curled to form hinge ears 51 through which extends a hinge pin 52.

The damper is of such dimensions that when closed over the auxiliary air inlet the main section 48 covers the auxiliary air inlet grille 41 thereby excluding the admission of air through the auxiliary air inlet and when fully opened to its other extreme position the damper closes or substantially closes the hot air passage between the inwardly spaced parts 37 of the bracket members 35 and the front and rear walls of the cabinet. The first mentioned position of the damper is illustrated in Fig. 5 and its second mentioned position is illustrated in dotted lines in Fig. 2. The damper may assume any position intermediate these extreme limits, one such position being illustrated in solid lines in Fig. 2.

For adjusting the damper and holding it in any position of adjustment, damper controlling means have been provided which conveniently may comprise a threaded stem 53 having a swiveled connection with the front wall of the cabinet and being threadedly engaged in a trunnion nut 54 which is provided with trunnions 55 that are swiveled in bracket arms 56, bolted or otherwise secured to the damper as by bolts and nuts 57. Conveniently the bracket arms 56 are angle shaped and their flanges or webs 58 extend parallel to each other and receive the trunnions of the trunnion nut with their flanges or webs 59 bolted to the damper.

The threaded stem 53 is formed with a spindle 60 which is rotatively mounted in a trunnion bearing 61 that is formed with coaxially disposed oppositely extending trunnions 62 that are swiveled in sockets 63 that may be formed by

striking up the metal of the front wall and the hinge plate 49 to form semi-circular depressions which when matched up provide cylindrical bearings for the trunnions. The metal of the front wall and hinge plate between the struck up portions is cut away for the reception of the trunnion bearing 61. A knob or handle 64 is secured upon the outer extremity of the spindle 60 as by a screw 65. The threaded stem is held against longitudinal movement with respect to the trunnion bearing by the knob on one side and the shouldered end of the threaded stem on the other side.

For indicating to an attendant the various positions of the damper, an arcuate indicator blade 66 is provided which has a flat portion 67 that is inserted between the damper 46 and the flanges 59 of the bracket arms 58 and secured thereto by the bolts and nuts 57. An arcuate indicator plate 68 having suitable indication marks thereon is secured upon the external face of the indicator blade 66 and cooperates with one of the grille bars 43a to indicate the position of the damper.

In the operation of the heater a fluid heating medium such as steam or hot water is supplied to the heat transfer element and air entering the open bottom of the cabinet becomes heated as it passes the heat transfer element, and rises in the cabinet when the damper is in its position closing the auxiliary air inlet or in any of its intermediate positions, and discharges through the outlet opening in the top of the cabinet.

If it is desired to have an unrestricted flow of hot air through the cabinet, the damper regulating knob 64 is turned in the proper direction to swing the damper into the closed position seen in Fig. 5, wherein the damper completely closes the passage through the auxiliary air inlet. With the damper located in the closed position just described, a maximum heat output is obtained.

If it is desired to reduce the heat output to a value approximating zero, the damper controlling knob is turned in the proper direction to swing the damper into the position shown in dotted lines in Fig. 2, wherein it practically closes the passageway through the cabinet at a place directly over the heat transfer element, and at the same time completely uncovers the auxiliary air inlet, permitting an unrestricted flow of cooler air into the cabinet, which is heated slightly by heat radiated from the damper, and rises through the cabinet, finally discharging from the outlet opening in the top thereof.

Having thus described my invention, it is obvious that various immaterial modifications may be made in the same without departing from the spirit of my invention; hence I do not wish to be

understood as limiting myself to the exact form, construction, arrangement and combination of parts herein shown and described, or uses mentioned.

5. What I claim as new and desire to secure by Letters Patent is:

1. A convection heater comprising in combination a cabinet having an air inlet opening, an air outlet opening and an auxiliary air inlet intermediate the air inlet and air outlet openings and spaced from said air inlet opening, oppositely disposed bracket members rigidly secured to the side walls of the cabinet and formed with inwardly spaced depending portions, a heat transfer element having fins thereon, the end-most ones of which are secured to said depending portions of the bracket members and together with said bracket members divide the lower part of the cabinet into a heating chamber and two end chambers, the heat transfer element having heating tubes in said heating chamber and headers in said end chambers, and a pivotally mounted damper extending between said inwardly spaced depending bracket portions and arranged in one position to close the auxiliary air inlet, and arranged in another position to close the passageway between the depending portions of the bracket members, said damper having means for adjusting it to any position between its limits of movement.

2. A convection heater comprising in combination a cabinet having an air inlet opening at the bottom and an air outlet opening at the top and an auxiliary air inlet in the front wall of the cabinet intermediate said inlet and outlet openings, bracket members rigidly secured to the side walls of the cabinet and being formed with depending portions spaced inwardly from the side walls, a heat transfer element in the cabinet below said bracket members and having headers disposed in the spaces between the side walls and the depending portions of the bracket members, said heat transfer element having also fluid conducting tubes connecting said headers and extending in the space between said depending portions of the bracket members, and L-shaped fins secured to said tubes and to said depending portions of the bracket members, and being formed with horizontal apertured flanges in which the headers are held, said depending portions of the brackets and L-shaped fins dividing the lower part of the cabinet into a heating chamber for the tubes and end chambers for the headers, and a damper extending between said depending inwardly spaced portions of the brackets and pivotally mounted on an axis disposed adjacent the lower edge of the auxiliary air inlet.

BENJAMIN SPIETH.
